UNITED STATES PATENT OFFICE

ALEX WASLEFF, OF CHICAGO, ILLINOIS

HERRINGBONE FLOORING

Application filed February 20, 1929. Serial No. 341,352.

This invention relates to improvements in interlocking flooring and more particularly to mosaic flooring of the type commonly known as herringbone, which is usually but not always, laid on mastic or similar composition.

The principal object of the invention is to provide a construction of tongue and groove flooring arranged to interlock with each other at abutting ends so as to hold the joints from lateral separation at these points after they are once laid.

My invention may best be understood by reference to the accompanying drawings, in which

15 Figure 1 is a view of a general design of the pattern in which my improved form of flooring pieces is utilized.

Figure 2 is an enlarged view showing details of the flooring pieces as they are arranged for fitting together.

Figure 3 is an enlarged detail view showing one end of one of the flooring pieces, and

20 Figure 4 is an enlarged detail showing another end of one of the flooring pieces.

Referring to details shown in the drawings, the flooring is made up of a series of flooring pieces arranged in herringbone pattern, as shown in Figure 1. The pieces are of the familiar tongue and groove type, but are provided with interlocking tongue and groove connections at abutting ends so as to hold the joints from lateral separation at these points after the flooring is laid.

25 In the embodiment illustrated herein, I provide two sets of pieces generally similar in construction but with slightly differing arrangement of interlocking devices at their opposite ends so as to fit with abutting pieces.

30 One series of pieces is indicated at 10, 10 and the other series at 11, 11, each series being arranged so that all of them extend in the same direction, and at a 90° angle to the other series.

45 Referring to the pieces forming one of the series, as for instance series 10, 10, each piece is provided with a tongue 12 along the major portion of its length and a groove 13 along the opposite side thereof. A tongue 14 is

50 also provided along substantially one-half of

one end of said piece and a groove 15 in substantially corresponding position at the opposite end of said piece 10. The pieces 11, 11 are similar to the pieces 10, 10 but with the position of the slots and grooves at the ends of the pieces in reversed order, i. e., at mutually opposite ends of the pieces, if the two pieces were arranged in parallel tongue-to-groove relationship with each other. Details of the end grooves and tongues of pieces 11, 11 are shown in Figs. 3 and 4 respectively.

55 As seen in the drawings, the series 10 and 11 are laid in end-to-side relationship with each other so that the tongue 14 of any series 10 piece fits into a groove 13a and engages a stop 13b on the adjacent side of the abutting series 11 piece. Groove 15 at the opposite end of the same series 10 piece will receive a relatively short tongue 16a in alignment with the main tongue 12a of the next piece of group 11.

60 The pieces of group 11 have similar end-to-side interlocking engagement with the pieces 10, by means of tongues 14a and grooves 15a, as shown.

65 A further interlocking engagement is provided between adjacent pieces of the same series by providing stops 17 and 17a respectively in grooves 13 and 13a, to be engaged by the ends of tongues 12 and 12a, as shown in the drawings. This arrangement restrains longitudinal displacement of adjacent pieces of the same group in either direction by reason of the stops 17 at one end of the grooves 13 and 13a, and stops 13b at the opposite ends.

70 The arrangement above described is such that the end of each piece is interlocked so as to restrain lateral movement of the abutting piece, and where all the pieces are so interlocked they are mutually held so as to eliminate spreading at the joints after they are once laid in place.

75 I claim as my invention:

1. Herringbone flooring comprising pieces each having a long and short tongue on one side and a groove on the opposite side, and a relatively short tongue on one end and a short groove on the opposite end, said short tongue and groove both being disposed adjacent the same side of the piece, and having mutually

interlocking engagement respectively with the side groove and the short side tongues of abutting pieces to restrain relative lateral movement of said abutting pieces in at least one direction.

5 2. Herringbone flooring comprising pieces each having a long and short tongue on one side and a groove on the opposite side, a tongue substantially one-half the length of one end and a groove substantially one-half the length of the opposite end, said last named tongue and groove both being disposed adjacent the same side of the piece, and having mutually interlocking engagement respectively with the side groove and the short side tongues of abutting pieces.

3. Herringbone flooring comprising two sets of pieces each having a long and short tongue and groove on opposite side, a tongue extending a part of the length of one end and a groove extending a part of the length of the opposite end, the end tongues and grooves of the two sets being on mutually opposite ends, and the end tongues and grooves of each set adapted to have interlocking engagement, respectively, with the side grooves and short tongues of abutting pieces of the other set.

4. Herringbone flooring comprising pieces each having a long and short tongue and groove on opposite side, and a relatively short tongue on one end and a short groove on the opposite end, said short tongue and groove having mutually interlocking engagement respectively with the side groove and short tongues of abutting pieces to restrain relative lateral movement of said abutting pieces in at least one direction, and stops in said side grooves engaged by the side tongues on laterally adjacent pieces restraining relative longitudinal movement therebetween.

Signed at Chicago, Ill., this 16th day of February, 1929.

ALEX WASLEFF.
